UNITED STATES PATENT OFFICE.

OLIVER MORSE, OF NEEDHAM, MASSACHUSETTS.

BED-PLATE FOR PAPER-PULP ENGINES.

SPECIFICATION forming part of Letters Patent No. 226,098, dated March 30, 1880.

Application filed February 19, 1880.

To all whom it may concern:

Be it known that I, OLIVER MORSE, of Needham, county of Norfolk, State of Massachusetts, have invented certain Improvements 5 in Bed-Plates for Paper-Pulp Engines, of which the following is a specification.

In this bed-plate the grinding-knives, which are thin flat blades of steel of uniform size, are bolted securely and permanently together 10 with intermediary division-bars of wood, which wear down simultaneously with the knives, the grinding-bed thus composed being contained bodily within a box or case adapted to closely receive it, and having provision for enabling 15 the bed to be raised to compensate for the wear upon its upper surface, the box being further provided with means for raising the bed as occasion requires, and which, in the present instance, is an adjustable shifting bot- 20 tom, capable of being raised and lowered by means of a screw-threaded rod, the head of which extends outside of the box and is readily accessible.

I consider my invention in this bed-plate to 25 consist in the movable grinding-bed as composed of alternate knives and division-bars, confined permanently together and contained within a box or case which has provision for raising the bed bodily as it wears.

30 The drawings accompanying this specification represent, in Figure 1, a perspective view, and in Figs. 2 and 3 vertical sections, of a bed-plate containing my invention, while Fig. 4 is a perspective view of the lifter-bar.

35 In said drawings, the grinding-bed is shown at A as composed of alternate bars of metal and wood bolted permanently together, the former being shown at a a, &c., as composed of sheet-steel and of uniform size, and constitut- 40 ing the grinding-knives, while the latter, b b, &c., are of like length and width as the steel blades, but of greater thickness, and constitute division-bars to separate the knives and provide the requisite grinding bed or surface, 45 the wood being of such soft texture as practically to offer no resistance to the grinding process.

Grinding-beds composed of alternate bars of steel and wood have been in use for many 50 years; hence I do not claim such construction, *per se*, though I consider the peculiar arrange-

ment of the knives, as hereinafter described, to be original with myself.

The grinding-bed A is deposited within a rectangular box or case, B, of cast-iron, of a 55 size to closely receive it and permit it to rise within it, the bed being steadied or clamped within such box by horizontal bolts c c, &c., passing through the box below the bed and playing within vertical slots d d, &c., in the 60 sides of the box, while, in addition to these main bolts, I employ a bolt, e, at each upper corner of the box outside of the bed, to confine the upper edges of the sides of the box together and closely hug the grinding-bed to 65 prevent shaking of the latter.

The bottom of the bed, which is flat, rests upon a shifting or adjustable bottom, which, in the present instance, is composed as follows: Upon the flat bottom of the box or case 70 B, I place a bar, C, of metal, composed of a series of blocks, a' a', &c., flat upon their under side, and having their upper surface formed of inclined planes e e, &c., of easy ascent, and sloping in a uniform direction, this lifter-bar C 75 being of less length than the interior of the box, and being moved longitudinally backward or forward in the latter by means of a screw-threaded rod, f, which screws through the entire length of the bar, and has a head, g, 80 which lies up against the front end of the exterior of the box.

By turning the rod f in one direction (to the right) the lifter-bar C is drawn toward the front end of the box, while reversing the movement 85 of the rod permits the bar to be pushed in the opposite direction; or by swiveling one end of the rod within the end of the box the bar would be pushed inward by the rotation of the rod.

Upon the top of each slope or incline e of 90 the bar C, I place a block or wedge, D, the upper surface of which is horizontal, in order that the series may provide a flat surface or base to receive the grinding-bed, and each block sloping on its under side to correspond with each 95 slope e of the bar.

The number of the wedge-blocks D D is equal to that of the bolts c, and each wedge is channeled transversely upon its upper side to receive a bolt, c, in order to prevent end-play of 100 the series of wedges—that is, of the shifting base or bottom of the grinding-bed, and com-

pel such bottom, as the wedge-bar is advanced by the rotation of the screw, to rise.

When the bed-plate above described is new the wedge-bar stands at its inmost extreme 5 within the box, and consequently the grinding-bed is in its lowest position and with its upper or grinding surface projecting somewhat above the upper margin of the box, the bolts *c* being screwed up sufficiently tight to prevent chattering of the bed within the box, but yet permit of such bed being raised within the box by means of the screw and wedge-bar.

In order that the head of the screw *f* may be readily accessible, an opening should be made 15 in the wall of the pulp-engine opposite such head, which permits of the use of a wrench, and by giving a slight turn to the screw daily to compensate for the wear upon the bed the latter always stands a uniform height above the 20 box—a matter of great importance.

I do not confine myself to the shifting bottom as composed of the wedge-blocks and lifter-bar, as this construction may be varied considerably without losing sight of the essential 25 feature of my invention, which I consider to embrace a bed-plate containing a grinding-bed adjustable vertically within its box and raised upon and by a shifting bottom susceptible of being actuated from the outside of the box. 30 For instance, in lieu of the wedge-bar and wedge-block, a series of eccentrics mounted upon horizontal transverse shafts may be employed to effect the elevation of the grinding-bed.

35 The arrangement or disposition of the knives and division-bars is peculiar—that is, I employ three parallel clamping or steadyng plates, *h* and *i*, the former being the outside binding-plates and the latter an intermediate plate, 40 which extends centrally of the bed and divides the two series of knives, and serves as a support for the inner ends of the latter. These two

series of knives are each arranged obliquely to the longest plane of the bed, and so as to converge at one end of the latter, as shown in Fig. 45 1 of the drawings. By this arrangement of the knives I produce a drawing cut at two different angles, which I have found highly efficient in preventing clogging of the bed.

I claim—

1. A bed-plate for paper-pulp engines composed of the following elements: a stationary outer box or case, an adjustable grinding-bed composed of alternating bars of wood and metal confined permanently together and deposited 55 within the box, and a shifting base or support intermediate between the bottom of the box and the adjustable bed, and adapted to raise the bed to compensate for wear.

2. The adjustable or shifting base or support 60 for the grinding-bed, composed of the lifter-bar with its series of inclined planes, and operated by a screw or its equivalent, and the wedge-blocks having correspondingly sloping bottoms to operate with such inclined planes, the blocks 65 being prevented from end-play within the box by suitable means, and the whole operating as explained.

3. The wedge-blocks *a'* *a'* *D* *D*, &c., and screw-threaded rod, in combination with and 70 operating between the bottom of the box and the under side of the grinding-bed, substantially as stated.

4. In combination, the outer box or case, the grinding-bed, the wedge or lifter bar and its 75 actuating-screw, the series of wedge-blocks between the bed and lifter-bar, and the bolts extending through the box and blocks, all substantially as shown and explained.

OLIVER MORSE.
